UNITED STATES PATENT OFFICE.

ALBERT BOARDMAN, OF HAMILTON, CANADA, ASSIGNOR TO WESTERN ELECTRIC COMPANY, INCORPORATED, OF NEW YORK, N. Y., A CORPORATION OF NEW YORK.

MACHINE FOR VACUUM-TUBE MANUFACTURE.

Application filed October 16, 1919. Serial No. 830,927.

To all whom it may concern:

Be it known that I, ALBERT BOARDMAN, a citizen of United States, residing at Hamilton, Canada, have invented certain new and useful Improvements in Machines for Vacuum-Tube Manufacture, of which the following is a full, clear, concise, and exact description.

This invention relates to a machine for manufacturing vacuum tubes and more particularly it relates to a machine for sealing the electrode supporting stems of vacuum tubes to the external glass bulbs or envelopes.

In the manufacture of vacuum tubes, particularly of the type containing more than one electrode, it is a common expedient to insert the electrode supporting stem in the glass envelope through an opening provided therefor in a constricted portion of the envelope and then to seal the constricted portion of the envelope to the stem.

An object of this invention is to provide means for insuring that the stem is sufficiently heated to prevent the glass from cracking when heat is applied from without the constricted portion to cause the constricted portion of the envelope to collapse and to be sealed to the stem.

The apparatus provided in accordance with the present invention comprises a rotatable shaft on which the electrode supporting stem may be mounted. A framework fastened to the shaft is provided for holding the bulb of the envelope by means of spring clips or the like. In order to prevent the constricted portion of the envelope from undergoing axial oscillations while the shaft is rotating, a petticoat may be provided on the shaft which petticoat fits snugly in the constricted portion of the envelope. In case such a petticoat is employed openings should be provided therethrough so that heat may be readily applied to heat the stem. The rotatable shaft on which the stem and envelope are mounted is supported by an arm which may be moved to the desired positions where heat may be applied to the stem and the constricted portion of the envelope in order to effect the sealing.

This invention will be better understood by the reference to the following detailed description taken in connection with the accompanying drawings in which Fig. 1 represents a sealing-in machine for vacuum tubes constructed according to the present invention.

Fig. 2 shows in detail a portion of Fig. 1. Fig. 3 is a cross-sectional view of the stem and the constricted portion of the envelope prior to the application of heat and Fig. 4 is a longitudinal view of the envelope 66 and the stem just after the sealing has taken place.

Referring more particularly to Fig. 1, the sealing-in machine comprises a plurality of arms 6, 7, 8, 9, 10 which are mounted on a rotatable shaft 11 which passes through the table 12 of the machine. Suitably supported on the arms 6 to 10 inclusive are the glass envelopes 15, 16, 17, 18 and 19 which surround the electrode supporting stems to be sealed thereto. Fig. 2 illustrates in detail the manner in which the glass envelope and the stem are supported by each of the arms. 21 is a rotatable shaft which is supported by the movable arm 9. A cog wheel 22 is provided at the lower end of the shaft 21 and is adapted to be engaged with cog wheel 23. Frictionally attached to the upper portion of shaft 21 is the electrode support 24, the flare portion 25 of which fits snugly over the end of the shaft. It is preferable that the upper end of the shaft 21 be made hollow so that the lead wires 27 may be inserted therein. The glass envelope 18 is held in place by a plurality of spring clips 29, 30, 31 which are fastened to a circumferentially incomplete member 33 which is attached to the rotatable shaft 21 by means of rods 34 and 35. 36 is a petticoat mounted on the shaft 21 of such a size that it fits snugly into the constricted portion 37 of envelope 18 and prevents any lateral motion thereof when the shaft is rotated. It is preferable that this petticoat 36 be provided with openings or slots through which heat may readily pass to reach the flared portion 25 of the electrode support.

This petticoat member above described is not a part of this invention, but is the invention of another and is described and claimed in an application of Otto Multer, Serial No. 324,957, filed September 19, 1919.

Referring now to Fig. 1, 45 is the position in which the glass envelope and the stem are mounted on the arms. After the envelope and the stem have been mounted on the arm of the machine the arm is moved to position 46 where according to the invention a flame 48 is provided for applying heat up through the openings in petticoat 36 to the stem.

This is also shown in Fig. 3. This preliminary heating of the steam is essential to prevent the stem from cracking when heat is later applied from without to collapse the glass envelope on the stem.

After the stem has been heated to the desired temperature in position 46 the arm is moved to position 50 where a flame 51 is provided for applying from without the 10 preliminary heating to the constricted portion on the glass envelope. In this position 50 the cog wheel 52 engages cog wheel 53 so that the glass stem and envelope may be rotated and the flame 51 applied uniformly to 15 all sides of the constricted portion of the envelope. Cog wheel 53 is shown to be connected by a belt 54 to a pulley 55 which is mounted on a shaft 56 driven by any suitable means not shown. After the preliminary 20 heating of the envelope at position 50 the arm is then moved into position 60, where three flames 61, 62 and 63 are provided for heating the constricted portion of the glass envelope to a still higher temperature. These flames are adjusted to give a 25 more intense and concentrated heat. Cog wheel 23 with which cog wheel 22 engages is driven by shaft 56 so that the flames 61, 62 and 63 may be applied uniformly to all sides 30 of the glass envelope where it is desired to have the envelope collapse to effect the sealing. The final heating of the glass envelope takes place in position 65 where six 35 still hotter flames 66 to 71 inclusive cause the constricted portion of the envelope to collapse and become sealed to the flared out portion of the electrode supporting stem. The glass envelope may be rotated in position 65 in a manner similar to that described 40 with reference to positions 50 and 60.

As soon as the glass envelope has been satisfactorily sealed to the electrode supporting stem the arm may then be moved to position 45. The tube with the sealed-in 45 stem may then be removed from its support. Another envelope and stem may be mounted on the arm and moved successively to positions 46, 50, 60 and 65 in order that they may be sealed together.

50 In order to insure that the arms will be stopped each time in the proper position with respect to the heating flames, each arm is provided with a projecting lug 75, which is adapted to be engaged with the stationary 55 slotted member 76 at position 65. A foot pedal 77 is provided for suitably releasing the lug 75 from the slot of member 76 whenever it is desired that the arms should be moved.

60 Fig. 3 is a longitudinal view showing the 65 relation of the constricted portion 37 of the envelope to the flared out portion 25 of the electrode supporting stem prior to the application of heat. Fig. 4 shows how the walls of the constricted portion 37 have collapsed

underneath to effect the sealing with the stem 25.

It is to be understood that this invention is not limited to the particular form described above, but it may be variously modified without departing in any wise from the spirit of this invention as defined in the appended claims.

What is claimed is:

1. A machine for sealing an electrode support in a glass envelope having a constricted portion, said machine comprising a movable supporting arm for said envelope and said electrode support, means for applying heat to said electrode support, and means for subsequently applying heat to the constricted portion of said envelope. 75

2. A machine for sealing a glass stem in a glass envelope having an apertured constricted portion, said machine comprising a movable arm, a rotatable shaft on said arm, supporting means on said shaft for said stem and said envelope, said stem being surrounded by said envelope, means for applying heat directly to the lower portion of 85 said stem through the opening in said constricted portion, and means for applying heat directly to said constricted portion to cause the walls of the constricted portion to collapse and become sealed to the heated 90 portion of said stem. 95

3. A machine for sealing a glass stem in a glass envelope having an apertured constricted portion, said machine comprising a movable arm, a rotatable shaft on said arm, 100 supporting means for said shaft for holding said stem in the desired relation to said envelope, said stem being surrounded by said envelope, means at one position of said arm for applying heat directly to said stem 105 through the opening in said constricted portion, and means at another position of said arm for applying heat directly to said constricted portion to cause the walls thereof to collapse and become sealed to the heated 110 portion of said stem.

4. A machine for sealing a glass stem in a glass envelope having an apertured constricted portion, said machine comprising a plurality of movable arms, a rotatable shaft 115 on each of said arms, supporting means on said shaft for holding the glass stem in the desired relation to said envelope, said stem being surrounded by said envelope, a heating flame adjacent one position said arms 120 may have for applying heat directly to said stem through the opening in said constricted portion, and a heating flame adjacent another position said arms may have for applying heat directly to said constricted portion 125 to cause the walls thereof to collapse and become sealed to the heated portion of said stem.

In witness whereof, I hereunto subscribe my name this Oct. 8, A. D., 1919.

ALBERT BOARDMAN.
